DESIGN FOR A DRESS

Jeannette Lippman, East Orange, N. J.

Application November 24, 1939, Serial No. 88,436

Term of patent 3½ years

To all whom it may concern:

Be it known that I, Jeannette Lippman, a citizen of the United States and a resident of the city of East Orange, in the county of Essex and State of New Jersey, have invented a new, original, and ornamental Design for a Dress, of which the following is a specification, reference being had to the accompanying drawing, forming a part thereof:

Fig. 1 is a front view of a dress showing my new design.

Fig. 2 is a rear view of the dress shown in Fig. 1. The characteristic feature of my design resides in the horizontal rows of straight tucks and novelty tucks comprising elliptical units and the arrangement of the spacing of the said straight and novelty tucks in combination with the cuffed sleeves and bordered neckline as shown.

I claim:

The ornamental design for a dress, substantially as shown and described.

JEANNETTE LIPPMAN.
